UNITED STATES PATENT OFFICE.

WILLIAM J. SIMMONS, OF ATLANTA, GEORGIA, ASSIGNOR TO KNIGHTS OF THE KU KLUX KLAN, OF ATLANTA, GEORGIA, A CORPORATION OF GEORGIA.

DESIGN FOR AN ATTESTATION SEAL.

Application filed May 25, 1925. Serial No. 13,564. Term of patent 14 years.

To all whom it may concern:

Be it known that I, WILLIAM J. SIMMONS, a citizen of the United States of America, residing at Atlanta, in the county of Fulton and State of Georgia, have invented a new, original, and ornamental Design for an Attestation Seal, of which the following is a specification, reference being had to the accompanying drawing, forming a part hereof.

In the drawing:

Fig. 2 is an edge elevation of the same, the frame being indicated by dotted lines.

I claim:

The ornamental design for an attestation seal, as shown.

WILLIAM J. SIMMONS. [L. s.]
